COMPOSITION OF MATTER

Elmer H. Hyde and Floyd D. Hager, Pittsburgh,
Pa., assignors to American Tar Products Com-
pany, Inc., a corporation of Delaware

No Drawing. Application July 15, 1930
Serial No. 468,201

7 Claims. (Cl. 167—45)

This invention relates to a composition of matter for use in preventing the growth of vegetation and more particularly for use in the destruction of weeds or other vegetation along railroad rights-of-way, aviation fields, orchards, highways, and so forth.

It has been found by us that the high boiling constituents of coal tar, principally those boiling above 350° C., are exceedingly effective in destroying plant tissue and in preventing germination in soil which has been treated therewith.

The product of the present invention may comprise the total distillate from coal tar which is driven off therefrom up to a temperature of substantially 800° F. to 1,000° F. It is preferred however to use the total distillate from soft or hard pitch, and preferably from hard pitch up to the formation of coke. The total distillate obtained from pitch when coking the latter in a suitable retort or by-product coke oven is called pitch oil.

The total distillate from soft pitch includes the higher boiling cuts of creosote oil which cuts may be used but which are not as effective as pitch oil. By soft and hard pitches we mean that pitches having melting points below 100° to 110° C. (cube in air method) are soft and pitches having melting points above those temperatures are hard.

The best results are obtained when a large percentage or all of the pitch oil fraction is used. This fraction contains such organic compounds of high molecular weight (over 200) as chrysene, pyrene, retene, pycene, truxene, chrysogene, and others including compounds containing nitrogen and oxygen. Compounds may be present which have a molecular weight of 200 and above. A mixture of these substances is more desirable than any of them singly. In other words, the entire pitch oil fraction is more desirable than portions thereof.

If desired, the heavier more viscous fractions may be diluted with a suitable diluent such as a volatile solvent, or water when the oil has been properly emulsified. The volatile solvents may be ether, benzene, carbon bisulphide, carbon tetrachloride, solvent naphtha, or the like, or mixtures of two or more of these. The lighter fractions of coal tar, as for instance those occurring in the aforesaid total distillate of tar, may also serve as diluents.

Other liquids, such as water gas tar distillate, or heavy petroleum oils may or may not be added to obtain the proper fluidity. The water gas tar distillate may be any well known fractions

of water gas tar, obtained for instance as distillates having a boiling point range of from about 100° C. to about 385° C. The proper fluidity may also be obtained by heating without the addition of a diluent or other liquid.

The following examples of compositions to be used for the purpose set forth are given by way of illustration:

Example 1.—20% by weight of pitch oil or heavy creosote oil are homogenized with about 80% by weight of water gas tar distillate having a boiling point range preferably of 100° C. to 385° C.

Example 2.—Pitch oil may be emulsified by the use of any suitable emulsifying agent such as soap, sulphonated oil, clay, bentonite, or the like. The emulsion should preferably be made as concentrated as possible and diluted to the required degree at the place where used. An emulsifying agent which gives good results and which is preferred is one containing water soluble salts of sulphonated pitch oil prepared as set forth in a copending application of F. D. Hager, Serial No. 471,095, filed July 26, 1930.

Such an emulsion, as made in the concentrated form, contains about 66.6% by weight of pitch oil, 8% of emulsifying agent, and 25.3% of water. The final product should be slightly alkaline. It may be diluted with the required amount of water before use. The amount of water necessary is governed, in a large measure, by the mode of application.

Another emulsifying agent which has been found useful in emulsions of pitch oil, is liquid sodium resinate prepared from black liquor obtained in the treating of wood pulp described in the copending application of E. H. Hyde filed May 27, 1930, Serial No. 456,293.

Any well known method of applying the composition of the present invention may be employed. The most effective method is to project the material over the desired area in the form of a fine spray or mist.

We claim as our invention:

1. A composition of matter, for use in preventing the growth of vegetation and in the destruction of weeds, comprising a mixture of all of the distillates of coal tar which are driven off therefrom up to a temperature of substantially from 800° F. to 1,000° F.

2. A composition of matter, for use in preventing the growth of vegetation and in the destruction of weeds, comprising a mixture of all of the distillates of coal tar pitch which are driven off

100

- therefrom up to a temperature of substantially from 800° F. to 1,000° F.
3. A composition of matter, for use in preventing the growth of vegetation and in the destruction of weeds, comprising a distillate from hard pitch derived from coal tar which distillate contains compounds having molecular weights over 200.
4. A composition of matter, for use in preventing the growth of vegetation and in the destruction of weeds, comprising a distillate from soft pitch derived from coal tar, which distillate contains compounds having molecular weights over 200.
5. A composition of matter, for use in preventing the growth of vegetation and in the destruction of weeds, comprising a distillate from coal tar pitch, in the form of an emulsion with water and an emulsifying agent, the said distillate containing compounds having molecular weights over 200.
6. A composition of matter, for use in preventing the growth of vegetation and in the destruction of weeds, comprising a mixture of compounds contained in the pitch oil fraction of coal tar, the said compounds having molecular weights of substantially 200 and above.
7. A composition of matter, for use in preventing the growth of vegetation and in the destruction of weeds, comprising a mixture of a diluent and compounds contained in pitch oil fraction of coal tar, the said compounds having molecular weights of substantially 200 and above.
